CLAIM

The ornamental design for an electronic device, as shown and described.

DESCRIPTION

FIG. 1 is a top-left-front perspective view of an electronic device, showing our new design, according to a first embodiment thereof.

FIG. 2 is a front elevational view of the first embodiment thereof.

FIG. 3 is a rear elevational view of the first embodiment thereof.

FIG. 4 is a right side view of the first embodiment thereof.

FIG. 5 is a left side view of the first embodiment thereof.

FIG. 6 is a top plan view of the first embodiment thereof.

FIG. 7 is a bottom plan view of the first embodiment thereof.

FIG. 8 is a top-right-front perspective view of the first embodiment thereof.

FIG. 9 is a bottom-left-front perspective view of the first embodiment thereof.

FIG. 10 is a top-right-rear perspective view of the first embodiment thereof.

FIG. 11 is a bottom-left-rear perspective view of the first embodiment thereof.

FIG. 12 is a top-left-front perspective view of an electronic device, showing our new design, according to a second embodiment thereof.

FIG. 13 is a front elevational view of the second embodiment thereof.

FIG. 14 is a rear elevational view of the second embodiment thereof.

FIG. 15 is a right side view of the second embodiment thereof.

FIG. 16 is a left side view of the second embodiment thereof.

FIG. 17 is a top plan view of the second embodiment thereof.

FIG. 18 is a bottom plan view of the second embodiment thereof.

FIG. 19 is a top-right-front perspective view of the second embodiment thereof.

FIG. 20 is a bottom-left-front perspective view of the second embodiment thereof.

(Continued)

FIG. 21 is a top-right-rear perspective view of the second embodiment thereof; and,

FIG. 22 is a bottom-left-rear perspective view of the second embodiment thereof.

In FIGS. 1-3 and FIGS. 5-11, the broken lines showing of various features on the top, left, front, rear, and bottom of the electronic device and unshaded areas therein are for the purpose of illustrating environmental structure, and the broken lines form no part of the claimed design. In FIGS. 12-15 and FIGS. 17-22, the broken lines showing of various features on the top, right, front, rear, and bottom of the electronic device and unshaded areas therein are for the purpose of illustrating environmental structure, and the broken lines form no part of the claimed design.
